UNITED STATES PATENT OFFICE.

FRANK K. SINGER, OF WHEELING, WEST VIRGINIA.

LIGHTNING-ARRESTER.

No. 814,482.

Specification of Letters Patent.

Patented March 6, 1906.

Application filed April 17, 1905. Serial No. 255,928.

To all whom it may concern:

Be it known that I, FRANK K. SINGER, a citizen of the United States, and a resident of Wheeling, in the county of Ohio and State 5 of West Virginia, have made certain new and useful Improvements in Lightning-Arresters, of which the following is a specification.

My invention is an improvement in lightning-arresters, being especially designed to 10 provide a lightning-protector for telephone-cables, &c.; and the invention consists in certain novel constructions and combinations of parts, as will be hereinafter described and claimed.

15 In the drawings, Figure 1 is a sectional elevation of an apparatus embodying my invention, and Fig. 2 is a detail longitudinal section of the fuse detached. Fig. 3 is a detail cross-section on about line 3-3 of Fig. 1.

20 In the construction shown I provide a frame having a metal bar or strap 16, bent at its lower end, forming the base portion 16^a. To the upper end of the frame 16 is secured at A the hard-rubber block B, the frame 16 25 extending along the inner side of the block near its lower end, while along the opposite side of the block extends the downwardly-projecting wing C' of the German-silver fuse and carbon holding plate C, whose top wing 30 extends across the upper end of the block B and over to and connects with the upper end of the fuse, as shown in Fig. 1.

In securing the plate C to the block B, I employ a screw D, which may be a brass machine terminal screw and is provided with the hexagonal nuts D', D'', and D''' and with the copper washer D^a. The depending wing C' of the plate C extends below the block B and alongside a line carbon block E, which fits 40 against a plate E', of mica, one thirty-second of an inch thick and which separates it from a carbon ground-plate E'', forming a spark-gap, as shown in Fig. 1.

45 As shown in Fig. 1, an insulating strip or block 23 is secured by a flat-head brass machine-screw 17 to the base 16^a of the frame, a nut 18 and copper washer 19 being provided on the screw 17 above the block 23 and a hexagonal brass block 26 being interposed between the insulating-block 23 and the base 16^a, as shown in Fig. 1. A brass terminal and fuse-socket 22, having a head 22^a at its lower end, fits from below in an opening in the insulating-block 23 and receives above 50 the said block a brass hexagonal block 20, which secures the brass terminal and fuse-

socket in place. This socket 22 has a threaded socket 22^b in its upper end, in which screws the threaded tenon at the lower end of the fuse-tube, as presently described. A 60 cable connection 21 is soldered in connection with the socket-block 22 at 25, and this connection 21, which may be a German-silver spring, fits at 21^a in a nick in the insulating-block 23 and being soldered at 25 to the block 22^b operates to prevent the block 22 from turning, and it also serves to hold the cable connection 21 from getting loose or out of place. A flat-head iron screw 24 may be employed for securing the base 16^a in place. 70

The fuse-tube is provided at its lower end with a brass terminal 38, having a depending threaded tenon which screws into the socket 22^b of the brass terminal 22, and at the upper end of the tube I provide a hexagonal nut 32, which binds the German-silver fuse-holder C or 6 against a metal cap 33 at the upper end of the fiber tube 37, to which cap 33 the upper end of the choke-coil 35 is soldered, such choke-coil being disposed around the upper 80 end of the fuse-tube 37 and being soldered at its lower end at 4 to the three-ampere ribbon fuse 30, which is disposed within the fuse-tube 37 and extends down therein to the brass terminal 22, as shown in Fig. 1. The choke-coil 85 35 comprises about twenty turns of No. 22 triple-covered wire, shellac - varnished, and the fuse-tube 37 is a fiber tube, shellac-varnished. The tube 37 is secured by a flat-head brass machine-screw 36 to the terminal 38, a 90 soldered connection 39 being effected between the lower end of the fuse 30 and the terminal 38, as will be understood from Fig. 1 of the drawings.

It will be noticed that the circuit in Fig. 1 95 is from the line to the choke-coil, through the choke-coil and three-ampere fuse to the cable.

In Fig. 1 I show a construction of the parts forming the spark-gap, in which the spark-gap occurs at the lower end of the block B, a 100 line carbon block E, mica plate E', and ground-plate E'' being provided, as before described.

Having thus described my invention, what I claim as new, and desire to secure by Letters Patent, is—

1. The combination substantially as herein described of the fuse-holding tube, the fuse within the tube, the choke-coil outside the tube, suitable terminals, and a spark-gap device in connection therewith. 105

2. In an apparatus, substantially as described, the combination of a frame, a non-

conducting block supported thereon and having a fuse-holding line-plate and spark-gap devices coöperating therewith, a fuse-holding tube connected at one end with the said line-
5 plate, a terminal block having a plate for connection with the cable, and connected with the other end of the fuse-tube, a fuse-strip in the said tube and a choke-coil wound about the tube and in electrical connection at one
10 end with the line-plate and at its other end with the fuse, substantially as set forth.

3. The combination with the frame having an upright and a base portion, a non-conducting block on the base portion, a terminal block supported by the non-conducting block and having a plate for cable connection, a non-conducting block supported on the upright of the frame, a line-connection plate, a screw securing said plate to the block, spark-
15 gap devices in connection with said plate, a tubular casing extending between said line-connection plate and the lower terminal, a fuse-strip in the lower portion of the tubular casing and a choke-coil around the upper portion of said tubular casing and having at one end electrical connection with the line connection and at its other end electrical connection, with the fuse-strip, substantially as set forth.

30 4. In a lightning-arrester the combination of a frame, a tubular non-conducting casing, a choke-coil on the outer side of the casing, a fuse within the casing and connected at one end with one end of the choke-coil, a terminal
35 with which the outer end of the choke-coil connects at one end of the casing, a terminal with which the outer end of the fuse connects at the opposite end of the casing, a ground-plate and spark-gap devices attached to the
40 frame and independent of the casing, substantially as set forth.

5. A lightning-arrester comprising an insulating-tube, a choke-coil on the outer side of said tube, a fuse within the tube, terminals
45 with which said coil and fuse are electrically connected, and a spark-gap and ground-plate independent of the fuse and choke-coil, substantially as set forth.

6. A lightning-arrester comprising a framing, a fuse-holding plate connected with the framing, a ground-block, devices connected with the fuse-holding plate and forming with

the ground-block a spark-gap, a terminal opposite the fuse-holding plate and having an attached cable connection, a casing extending between the fuse-holding plate and opposite terminal and having an insulating-tube, a fuse therein and connected with the lower terminal and a choke-coil surrounding the insulating-tube and having electrical connection at one end with the fuse within said tube and electrical connection at its other end with the fuse-holding plate, substantially as set forth.

7. A lightning-arrester, comprising a non-conducting base-block, a terminal block supported by said base-block and having a plate for cable connection, a line-connection plate, a non-conducting block to which said plate is secured, spark-gap devices in connection with the line-connection plate, a tubular casing extending between said line-connection plate and the terminal on the base-block, a fuse-strip in one end of said tube, and a choke-coil around the other end of the tube
70 and having at one end electrical connection with the line connection and at the other end electrical connection with the fuse-strip, substantially as set forth.

8. In a lightning-arrester the combination with the opposite terminals and insulating-supports therefor, of the combined fuse and choke-coil extending between said terminals and electrically connected therewith, the said fuse and choke-coil comprising the tube, the
85 fuse within the tube, and the choke-coil outside the tube and connected with the fuse, substantially as set forth.

9. In a lightning-arrester the combination of opposite insulating-blocks, a terminal block supported by one insulating-block, a terminal plate supported by the other insulating-block, a ground-block and means carried by the insulating-block supporting the plate and coöperating with the ground-block
90 in forming a spark-gap, and the combined fuse and choke-coil extending between the terminal block and terminal plate, substantially as set forth.

FRANK K. SINGER.
